Primary Examiner — Janice Patyk(74) *Attorney, Agent, or Firm* — Plumsea Law Group, LLC(57) **CLAIM**

The ornamental design for a light element for a loudspeaker as shown and described.

DESCRIPTION

FIG. 1 is a first perspective view of a light element for a loudspeaker, showing the new design;

FIG. 2 is a second perspective view thereof; and,

FIG. 3 is a third perspective view thereof, shown in an alternate environment.

The evenly spaced broken lines form no part of the claimed design. The dash-dot broken lines immediately adjacent the claimed areas in the views represent boundaries of the claimed design and form no part thereof.
